[57] **CLAIM**

The ornamental design for a bottle, as shown and described.

DESCRIPTION

FIG. 1 is a front elevational view of a bottle embodying our new design, the rear elevational view being a mirror image thereof;

FIG. 2 is a side elevational view looking from the right of FIG. 1;

FIG. 3 is a side elevational view opposite the view of FIG. 2;

FIG. 4 is a top plan view thereof; and,

FIG. 5 is a bottom plan view thereof.

The broken line showing of a bottle neck in FIGS. 1, 2, 3 and 4 is for illustrative purposes only and forms no part of the claimed design.
